His Atty.

UNITED STATES PATENT OFFICE.

CHARLES D. OATMAN, OF BROOKLYN, NEW YORK.

NOZZLE FOR BAGS OR POUCHES.

SPECIFICATION forming part of Letters Patent No. 430,746, dated June 24, 1890.

Application filed March 19, 1890. Serial No. 344,494. (No model.)

To all whom it may concern:

Be it known that I, CHARLES D. OATMAN, of Brooklyn, county of Kings, State of New York, a citizen of the United States, have invented an Improved Nozzle for Bags and Pouches, of which the following is a full, clear, and exact description, reference being had to the accompanying drawings, forming part of this specification.

10 My invention relates to a nozzle for bags and pouches; and my invention consists in a tube or nozzle adapted to be closed or filled by a stopper or cork, and an annular flange on said tube adapted to be secured to the inner side of the bag end, while the neck of the bag is gathered up and secured to and about the tube or nozzle beyond said flange.

Figure 1 is a view in perspective of a bag or pouch to which my improved nozzle is applied. Figs. 2 and 3 are respectively a side elevation and a plan of a nozzle containing my invention.

A is my improved nozzle, fabricated from thin metal or stiff paper or card-board, and 25 composed of the tube a and the annular flange a' at the lower end of the tube. The flange is preferably dishing or downwardly inclined from its junction with the tube to its rim, and it is adapted to be attached to the material 30 of a bag or pouch at the inner side of an end thereof. This may be accomplished by cutting the tongues a² from the flange-body and bending them upwardly at an angle thereto, so that they may be passed through the cloth 35 or other material of the pouch end and turned down upon the outer surface of the bag, as shown in Fig. 1. Any other known and equivalent means may be employed in place of the tongues a² for attaching the flange to the bag 40 end on the interior thereof.

I find it desirable to form an annular or equivalent projection a³ on the exterior surface of the tube a immediately above its juncture with the flange a', as shown, so that when 45 the mouth of the bag is drawn up to the tube—as, for example, by an ordinary drawing-spring (indicated at a⁴)—the gathered folds and string may lie below the projection and between it and the flange, thereby serving to 50 assist in preventing the escape of the nozzle from its seat in the bag end.

It is to be understood that when the nozzle is placed in the mouth of the bag and the

material of the bag at the mouth thereof is drawn up to the tube above the flange, as set 55 forth, the flange is then secured to the bag-wall around the tube, as by the tongues a², in the manner specified. The nozzle A thus fixed in a bag B is adapted to be closed by a cork or stopper C.

60 The described nozzle is specially adapted for use in connection with bags or pouches for holding tobacco or similar material, and it is intended to be placed in the bags when they are originally packed at the factory, and 65 to thereafter serve to discharge the contents of the bag as the same may be required for use.

In discharging the contents of the bag the flange not only serves to hold the nozzle in 70 place in the bag end as the bag is gradually emptied, and consequently more or less collapses, but also to guide the contents to the tube a, so that said contents may be readily discharged through the same.

75 What I claim as my invention, and desire to secure by Letters Patent, is—

1. A nozzle for collapsible bags or pouches, consisting of a tube a, adapted to be closed by a stopper, and having a flange a' at its 80 lower end, provided with the flexible tongues a² on its upper face for securing the same to the bag, substantially as and for the purpose set forth.

2. A nozzle for collapsible bags or pouches, 85 consisting of a tube a, having an annular flange a' at its lower end, provided with the flexible tongues a² on its upper face for securing the same to the bag, and having a peripheral projection a³ above the joint thereof with 90 the flange, substantially as and for the purpose set forth.

3. In a bag or pouch, the combination there-with of a tube a, reaching through its mouth, a flange on said tube having the tongues a² 95 passing through and turned down upon the bag-wall around the mouth, and a peripheral projection a³ on the tube, between which and said flange the bag-mouth is in contact with said tube, substantially as and for the purpose set forth.

CHARLES D. OATMAN.
